ATTORNEY

UNITED STATES PATENT OFFICE.

FRANK JOSEPH ROSENBERG, OF LOS ANGELES, CALIFORNIA.

DESIGN FOR A TOBACCO-PIPE.

No. 37,737.

Specification for Design.

Patented Dec. 19, 1905.

Application filed August 22, 1905. Serial No. 275,280½. Term of patent 3½ years.

To all whom it may concern:

Be it known that I, FRANK JOSEPH ROSENBERG, a citizen of the United States, residing at the city of Los Angeles, in the county of Los Angeles and State of California, have invented a new, original, and ornamental Design for a Tobacco-Pipe, of which the following is a specification, reference being had to the accompanying drawing, forming a part thereof.

The figure is a perspective view showing the design of a tobacco-pipe.

I claim—

The ornamental design for a tobacco-pipe as shown.

FRANK JOSEPH ROSENBERG. [L. s.]
